UNITED STATES PATENT OFFICE.

JOHN M. WADDELL, OF GREENFIELD, OHIO.

SHOW-CASE.

946,626.

Specification of Letters Patent. Patented Jan. 18, 1910.

Application filed September 19, 1908. Serial No. 453,798.

To all whom it may concern:

Be it known that I, JOHN M. WADDELL, a citizen of the United States of America, and resident of Greenfield, county of Highland,

5 State of Ohio, have invented certain new and useful Improvements in Show-Cases, of which the following is a specification.

The object of my invention is a show case the front of which the vendor may open 10 easily, so that the customer himself may take the article purchased readily from the case. This object is attained by the means described in the specification and illustrated in the accompanying drawings in which,

15 Figure 1 is an end view of a case embodying my invention with the end of the case removed and with the bottom and one side of the revolving lid shown in section. Fig. 2 is a rear elevation of the case. Fig. 3 is a plan 20 view thereof, showing the case partly broken out, to expose the locking lever.

25 Referring to the parts: each end of the case consists of a frame, the front half, A, of which is in the shape of a quadrant of a circle, and the rear half, A', of which is a rectangle of a width equal to or greater than radius of said circle. The top, B, of the case is supported by the rectangular part of the ends.

30 Between the bottom, C, of the case and the rear edge of the top, B, sliding doors, D, D', are mounted.

35 The opening in the front of the case between the top, B, and bottom, C, may be closed by a rotary lid, E. Lid, E, consists of end pieces e—e' of the shape of a quarter of a circle, between which curved glass, e², is mounted.

40 A radial arm, G, of the size of the radius of the curved lid, E, is pivoted to each end of the case, at, g, the center of rotation of the lid, and is secured at its opposite forked end, g', to the ends, e, and, e', respectively of the lid. One of the arms, G, has pivoted to it at, 45 g², an actuating lever, H, which extends to the rear of the case and terminates in a handle, h. At, h', a fulcrum arm, K, is pivoted to lever, H, the lower end of the fulcrum arm being pivoted to the end of the case at a 50 point, k, which is at the same distance from g, that g², is distant from, g, or the distance, g—k, may be made greater than the distance, g—g².

55 The door, D, has a notch adjacent to lever, H. Said door has a coiled spring, d, to close it. Spring, d, has a hook engaging

a pin, d', from which it may be readily disengaged when it is desired to open door, D.

A horizontal locking lever, M, is pivoted at, m, to the bottom of the case, and has at 60 its forward end a hook, m', to enter a slot in the center of the lid, E, and to engage a pin, e³. Lever, M, is held normally in engagement with the pin, e³, by a spring, m².

The operation of the device is as follows: 65

When a customer desires to purchase a cigar, the clerk, with one hand, moves the lever, M, to unlock the lid, E, and by a pressure downward upon the lever, H, causes the arms, G, to be rotated rearwardly, there- 70 by opening the lid, E. The customer then has free access to the cigars and may pick the one he desires from the box, without the clerk's removing a box from its arrangement in the case. The movement of the 75 lid, E, in no wise affects the top, B, of the case, from which, therefore, any articles which might be lying thereon need not be removed; another advantage of my revolving lid is that the merchant may arrange 80 his wares from the front of the case so as to make the display he desires.

What I claim is:

1. The combination of a case having an open front, a rotatory lid adapted to close 85 the front, a radial arm at each end of the case, the radial arms being pivoted at one end to the case and being secured at the other end to the lid, a fulcrum arm pivoted to one end of the case and an actuating lever 90 pivoted to the fulcrum arm and to one of the radial arms and projecting to the rear of the case.

2. In a show case the combination of a rotatory lid for the front of the case, a lever 95 pivoted within the case so as to move in a vertical plane adjacent to the end of the case and connected at one end to the lid and projecting at the other end to the rear of the case to regulate the movement of the 100 lid, a reciprocating door for the rear of the case having a notch at one end which forms with the end of the case an opening through which the lever projects, and a means for locking the reciprocating door in its closed 105 position, whereby when the door is closed the lever is locked from movement.

JOHN M. WADDELL.
